UNITED STATES PATENT OFFICE.

THERON S. E. DIXON, OF CHICAGO, ILLINOIS.

HASP-LOCK.

SPECIFICATION forming part of Letters Patent No. 295,912, dated April 1, 1884.

Application filed November 26, 1883. (No model.)

To all whom it may concern:

Be it known that I, THERON S. E. DIXON, of the city of Chicago, county of Cook, and State of Illinois, have invented a new and useful Improvement in Hasp-Locks, of which the following is a description, reference being had to the accompanying drawings, in which—

Figure 1 is a plan view of a lock provided with my improvement. Fig. 2 is a top view of a modification of the same. Fig. 3 is a front view of a portion of the shackle in another modification. Fig. 4 is a plan view of a modification. Fig. 5 is a plan view of another modification.

15 The object of my invention is to dispense with the employment in connection with a lock of a separate hasp or hasp and pivoted hook; and it consists in certain improvements, which will hereinafter be described, and pointed out in the claims.

In the form of my invention illustrated in the drawings, A represents the lock, which may be of any suitable style, form, or construction. B is the shackle, bow, or link of the lock, and which in the ordinary construction is pivoted to the lock at a, the forward end of the shackle being provided with any appropriate slot or notch for the reception of the bolt within the lock. The shackle or link 30 B is provided with an arm, C, extending outward therefrom, preferably in the direction shown in the drawings, and this arm C is provided at its outer end with a hole, D, through which a staple may be driven, to secure it to the door or other structure to which it may be attached. In this construction the shackle or link B, with its arm C, serves not only as a bow for the lock, but also as a hasp and hook as well, thus dispensing with the necessity for 40 the additional employment of these articles in connection with the lock.

In operation, when it is desired to fasten the shackle, the lock A is swung around upon the pivot a, and the outer end of the shackle 45 is inserted within the staple E, when the lock is returned to place, so as to inclose the outer end of the shackle, and the key is turned. Whenever desired, the lock may be left unlocked, when the shackle B and arm C serve as 50 a hook retained in place by the staple. In such case another advantage is secured, as the

lock cannot be lost or mislaid, but is always retained in its place ready for use. Another advantage secured by this construction is, that whenever desired the shackle B and arm C 55 may be so attached as to place the lock bottom upward, as shown in Fig. 4, when the rain cannot penetrate within it and the rusting of the mechanism is avoided. In the modification of my invention shown in Fig. 60 4 the shackle B is provided with a short projection or arm, b, which may be inserted as a hook in the staple when the lock is left unlocked.

If preferred, the shackle B or arm C may 65 be provided with a projection or offset, b', projecting either flush with the back plate of the lock or slightly beyond the same, as shown in Fig. 2, so as to permit of greater ease of movement upon the surface to which it is applied when passing in and out of the staple. Another advantage secured by this form of construction is, that when the lock is left unlocked, and the arm C and the shackle B serve as a hook, the shackle or hook B is thrown 70 by the offset b' outward against the inclosing staple, so that the projection at its end at the side thereof (shown in Figs. 2 and 3) presses against the lower edge of the staple, and the hook is thus effectually held in place under 75 any accidental jar or blow upon the door. By the use of the offset b' the lock is also protected from abrasion against the door to which it is applied in locking or unlocking, and is also retained pendent in a position parallel to 80 the surface to which it is applied. In the preferable construction the forward end of the shackle, which enters the lock, is beveled or rounded off upon its outer side, as shown at b' in Fig. 3, which materially assists its entry within a closely-driven staple.

My invention is illustrated in Fig. 1 as applied to an ordinary padlock; but it may be used in connection with a variety of locks and locking mechanisms. Thus in Fig. 5 it is 95 illustrated as applied to the link of the well-known style of lock in which the link, instead of being pivoted, slides up and down in the body of the lock. If preferred, the arm C may be made detachable from the 100 shackle B by a screw-connection or otherwise, or they may be united by a pivot; but the

form illustrated in the drawings is deemed the better construction.

Having thus described my invention, what I claim as new, and desire to secure by Letters Patent, is—

1. As an improved article of manufacture, a lock the shackle or link of which is provided with a projecting arm for the purpose of a hasp, substantially as described.

2. As an improved article of manufacture, to a lock the shackle or link of which is provided with an arm for the purpose of a hasp, and also a projection or offset upon its rear side, substantially as described.

HERON S. E. DIXON.
